US0D1095447S

(12) **United States Design Patent** (10) **Patent No.:** **US D1,095,447 S**
(45) **Date of Patent:** **** Sep. 30, 2025**

(54) **ELECTRICAL CONNECTOR**

(71) Applicant: **STÄUBLI ELECTRICAL CONNECTORS AG**, Allschwil (CH)

(72) Inventors: **Olivier Piard**, Luzancy (FR);
Guillaume Ferrara, Koetzingue (FR);
Mathieu Chaligné, Vieux-Ferrette (FR)

(73) Assignee: **Stäubli Electrical Connectors AG**, Allschwil (CH)

(**) Term: **15 Years**

(21) Appl. No.: **35/520,880**

(22) Filed: **May 12, 2023**

(80) **Hague Agreement Data**

Int. Filing Date: **May 12, 2023**

Int. Reg. No.: **DM/233013**

Int. Reg. Date: **May 12, 2023**

Int. Reg. Pub. Date: **May 17, 2024**

(51) **LOC (15) Cl.** **13-03**

(52) **U.S. Cl.**

USPC **D13/146**; D13/147

(58) **Field of Classification Search**

USPC D13/107, 119-120, 133, 137.4, 139.7,

(57) **CLAIM**

The ornamental design for an electrical connector, as shown and described.

DESCRIPTION

5. Electrical connector

5.1 : Back

5.2 : Bottom

5.3 : Top

5.4 : Right

5.5 : Front

5.6 : Left

5.7 : Perspective back

5.8 : Perspective front

The broken lines in the reproductions illustrate portions of the electrical connector that form no part of the claimed design.

1 Claim, 8 Drawing Sheets
